RAILWAY MAIL HANDLING APPARATUS

John W. Owen, Columbus, Ohio

Application April 27, 1942, Serial No. 440,717

1 Claim. (Cl. 258—15)

This invention relates to new and useful improvements in mail dropping and catching apparatus for railways, the principal object of the invention being to provide a single apparatus which will automatically catch a pouch of mail and simultaneously deliver a pouch.

Another important object of the invention is to provide a mail handling apparatus of the character stated which will be positive acting and not susceptible to the ready development of defects.

In the drawings:

Figure 1 represents a fragmentary side elevational view of a mail car showing a door with the rolling stock attached unit in place, and in proper relationship with respect to the station located unit, shown to the left.

Figure 2 is a fragmentary horizontal sectional view taken substantially on the line 2—2 of Figure 1.

Figure 3 is a fragmentary horizontal sectional view through one of the holders and through a mail pouch held therein.

Figure 4 is a longitudinal vertical sectional view through one of the holders shown without a mail pouch.

Figure 5 is a cross sectional view taken substantially on the line 5—5 of Figure 3.

Figure 6 is a perspective view of the spring used with the holders.

Referring to the drawings wherein like numerals designate like parts, it can be seen in Figure 1, that numeral 5 generally refers to a mail car having a door opening 6 in a side thereof. Numeral 7 denotes a supporting bar which spans the door 6 and projecting outwardly from this bar 7 is an arm 8 upon which a holder unit generally referred to by numeral 9 is mounted, this unit 9 being in complement to a unit 10 which is supported by a post 11 and arm 12 at a railway station or some other pick-up and delivery point.

It is to be understood that each of the holders 9, 10 is of like construction and each includes a pair of jaws 13, 13 having arcuate-shaped inner faces a, a for hugging the intermediate portion of a mail pouch 14. Leg members 15, 15 extend from the jaws 13, 13, the jaws and legs being connected by inwardly offset portions 16 which are pivotally secured as at 17 to the corresponding arm 8 or the arm 12, in juxtaposition as shown in Figure 3.

The legs 15, 15 are slotted adjacent the neck portions 16 and through these slotted portions extends the bight portion b of a U-shaped strip spring 18, the leg portions of which are disposed

into channels 19 in the outermost portions of the legs 15, 15.

As can be seen in Figure 3, the free end portions of the legs 15, 15 diverge outwardly as at 20, these portions 20 serving to define a mouth for guiding mail pouches into the confines of the legs 15, 15.

One leg 15 of each unit 9, 10 has a recess 21 in which one end of a prop 22 is pivotally mounted, the other end of the prop being adapted to abut the opposed portion of the complementary legs 15 to hold the legs in open position as suggested in Figure 3 and maintain the jaws 13, 13 gripping a mail pouch 14. This setting is required when it is desired to deliver and receive mail pouches.

Referring now to Figure 2, it can be seen that the units 9, 10 are in reverse relation with respect to their position, it being observed that the legs 20 of the units are pointed toward each other.

A mail pouch will be positioned between the jaws 13, 13 of each unit 9, 10.

When the pouch of the unit 9 strikes the prop 22 of the unit 10, the doors 13, 13 of the unit 10 will be released and the spring 18 will serve to spread the same. The same action takes place with respect to the pouch in the unit 10. The prop 22 of the unit 9 will ride the pouch in the unit 10 become tripped by contact, simultaneous with the aforesaid operation so that the pouch of the unit 9 will be released to be held between the legs 15, 15 as the pouch of the unit 10 to be picked up by the mail car is gripped by the legs 15, 15 of the unit 9.

As is shown in Figure 3, it is preferable that the arms 8 and 12 be of sectional construction, with one section telescoping the other and having openings therein for receiving a pin, so that the position of the corresponding unit can be reversed whenever desired, as for instance, to take care of a single track railway where trains move in opposite directions thereon. Obviously, by unloosening the pin and rotating the unit and reinserting the pin the unit can be made to serve traffic moving in an opposite direction.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

In a mail bag delivery and pick up apparatus, a railway car unit, a railway side stationary unit,

each unit comprising a unit supporting arm, a pair of elongated members of compound curvature pivotally mounted upon the arm side by side intermediate the ends thereof and forming two pairs of jaws upon opposite sides of said arm, respectively, a U-shaped leaf spring between the jaws of one pair tending to close said pair and open the other pair of jaws, a prop between the

5 jaws of said one pair adapted to hold the same open, said prop being pivotally mounted to one of the jaws of said one pair for swinging into ineffective position by impact of a mail bag thereagainst, said arm comprising axially aligned telescopic sections, one rotatable in the other to reverse the position of the unit mounted thereon.

JOHN W. OWEN.
